UNITED STATES PATENT OFFICE.

THOMAS BURNS BAYLESS, OF LEXINGTON, KENTUCKY.

FIREPLACE-HEATER.

SPECIFICATION forming part of Letters Patent No. 728,355, dated May 19, 1903.

Application filed October 30, 1902. Serial No. 129,388. (No model.)

To all whom it may concern:

Be it known that I, THOMAS BURNS BAYLESS, a citizen of the United States, residing at Lexington, in the county of Fayette and 5 State of Kentucky, have invented certain new and useful Improvements in Fireplace-Heaters; and I do hereby declare the following to be a full, clear, and exact description of the invention, such as will enable others skilled 10 in the art to which it appertains to make and use the same.

This invention relates to air-heating devices of that class which are mounted in fireplaces or chimneys and through which fresh 15 air is conducted past or in close proximity to the fire or hot part of the fireplace and then discharged in heated condition into the room, whereby heat is obtained not only by direct radiation from the burning fuel, but also by 20 discharge of such heated air, as well as by radiation and reflection from the outer walls of the air-heater.

The object of the present invention is to provide an improved and exceedingly simple 25 and efficient device of this character which will permit utilization of the heat generated in the fireplace in a most thorough and economical manner.

The invention will first be described with 30 reference to the accompanying drawings, which form a part of this specification, and will then be pointed out more particularly in the annexed claim.

In said drawings, Figure 1 is a front view of 35 a fireplace having my improved heater mounted therein. Fig. 2 is a perspective view of the heater detached. Fig. 3 is a central vertical cross-section through the fireplace looking from the left of Fig. 1. Fig. 4 is a central vertical cross-section through the fireplace looking from the right of Fig. 1.

The letter A denotes a fireplace of ordinary construction, and B and C designate the front and rear chimney-walls, while D indicates a 45 grate for support of fuel, E the ash-pit beneath the same, and F a rear fire-brick or lining for protecting the heater from the fire. In place of a grate suitable andirons or fire-dogs may be used where wood logs are to be burned, 50 or suitable gas or oil fuel burners may be employed.

My improved air-heater consists in the main

of an upright wide but thin or flattish casing G, fitting, preferably, in the back of the fireplace and having a suitable opening or pipe 55 at the bottom for admission of fresh pure air and having a suitable opening or pipe at the top for discharge of hot air into the room or connected with a flue or flues for conducting the heated air to hot-air registers or radiators 60 in other parts of the building, the heater thus acting on the principle of the ordinary furnace. In the present illustration of the invention an air-inlet pipe H depends from the bottom of the casing into a fresh-air chamber 65 J beneath the fireplace, and a flue K extends from the upper part of the casing through the side of the chimney and into the room, into which hot air is thus discharged, while a flue L is also shown for conducting hot air to an 70 upper room. This casing G may rest in the floor of the fireplace or may be supported with its bottom above the floor, and it may be fastened to the chimney-wall or otherwise mounted in place. The fire-brick F is located 75 between the grate and the lower front part of the casing to prevent the fire from burning or injuring the same. The rear face or wall of the casing is usually flat or plane, as shown, so as to fit closely against the rear chimney- 80 wall, while the front face or wall of the casing is formed with a forward-projecting part g, preferably immediately above the fire-brick, whereby the thin or shallow space between the front and rear walls of the casing is increased 85 above the grate, while a horizontal shoulder g' is also provided, which rests upon the upper edge of the fire-brick, by which the casing may thus be rigidly supported in place. The casing has also a forwardly-inclined top 90 portion g², preferably of the same thickness or cross-dimension as the part g. This not only conforms to the ordinary construction of the rear chimney-wall at top of the fireplace, but such forwardly-inclined part of the 95 casing overhangs the fire, and is thus acted on by the ascending heat, so that the air in the casing is continually heated as it rises until it reaches its discharge pipe or flue. The flue K, as shown, extends laterally from one end 100 of this inclined part g² of the casing and upwardly through the side of the chimney, so that the hot air will readily ascend therethrough. The fresh air admitted through the

- lower inlet-pipe passes up through the casing in a wide thin sheet, which is thus heated easily to a very high degree. In the lower part of the casing the air is heated at the outset by reason of its proximity to the fire, and is thus expanded as it ascends into the upper thicker or increased part of the internal chamber of the casing, and as it passes up through said upper part of the casing and forwardly-inclined or overhanging part still in a comparatively thin sheet it takes up more heat from the rising flames and heat from the burning fuel, and this is expanded more and more, so that it is forced up through the flues and discharged.
- It will be observed that the air-inlet pipe H is located at the left-hand side of the heater or casing, while the air-exit flue is located at the opposite or right-hand side. By this arrangement the air is prevented from rising quickly in a vertical column and is compelled to spread out and pass in a sheet across the whole width of the casing, thus taking up a great amount of heat.
- As is well known, in the ordinary fireplace about two-thirds of the heat goes up the chimney and is wasted. By means of my improved heater nearly half of this waste heat may be utilized.
- The heater may be made of cast-iron, preferably in an integral or unitary part, and the flues made of sheet metal, or both may be constructed of any suitable metal and in any suitable manner. Two small knobs g^3 are

shown at the lower front part of the casing. 35 These are for screwing or attaching the rear of the grate thereto; but they are not essential. The device is also susceptible of various minor changes in details of construction and arrangement.

Having thus fully described my invention, what I claim as new, and desire to secure by Letters Patent of the United States, is—

A fireplace-heater consisting of a wide thin casing adapted to fit in the back of the fireplace, and through which air ascends in a thin sheet, said casing comprising in a unitary structure a vertical member having a flat back and a front projecting abruptly forward at its upper part, thus providing a horizontal shoulder to rest on the fire-brick placed against the lower front and enlarging the internal space transversely above the fire-brick, and a forwardly-inclined or overhanging member extending from the top of said vertical member and of substantially the same thickness as the upper part of the latter, together with a lower pipe or opening for admission of fresh air and an upper flue or opening for discharge of hot air leading from said forwardly-inclined member, substantially as described.

In testimony whereof I affix my signature in presence of two witnesses.

THOMAS BURNS BAYLESS.
